UNITED STATES PATENT OFFICE.

GEORGE J. FRITZ, OF ST. LOUIS, MISSOURI.

STAVE-DRESSING MACHINE.

SPECIFICATION forming part of Letters Patent No. 309,341, dated December 16, 1884.

Application filed July 17, 1884. (No model.)

To all whom it may concern:

Be it known that I, GEORGE J. FRITZ, of the city of St. Louis, in the State of Missouri, have invented a certain new and useful Improvement in Stave-Dressing Machines, of which the following is a full, clear, and exact description, reference being had to the accompanying drawings, forming part of this specification, and in which—

10 Figure 1 is a side elevation. Fig. 2 is a top view. Fig. 3 is a section taken on line 3 3, Fig. 2, not showing the supporting-legs of the machine. Fig. 4 is a similar view taken on line 4 4, Fig. 2. Fig. 5 is an enlarged elevation of the delivery-rolls. Fig. 6 is a section taken on line 6 6, Fig. 8. Fig. 7 is an enlarged top view of the feed-rolls, cutters, and delivery-rolls, showing also one side of the frame of the machine; and Fig. 8 is a section 20 taken on line 8 8, Fig. 7.

My invention relates to a machine for concaving and convexing staves; and it consists in features of novelty hereinafter fully described, and pointed out in the claim.

25 Referring to the drawings, A is the frame of the machine, having supporting-legs A'.

B represents the main driving-shaft of the machine, supported in journal-boxes B', secured to the frame A. It has a tight and loose 30 pulley, B² B³, to receive the main driving-belt. It also has a large pulley, C, connected by means of a belt with pulleys D H on the cutter-shafts D' H', the belt passing, as shown in Fig. 1 by dotted lines, from the top of the pulley C over the upper pulley, D, thence under same and over the lower pulley, H, and thence back and under the pulley C. The shafts D H are journaled in boxes D² H², secured to the frame A, and on them at one side of the machine are cutter-heads D³ H³, provided with knives or cutters D⁴ H⁴, the upper cutter-head, D³, forming the inner or concave surface of the stave as the blank passes through, the knives having round cutting-edges, and the 40 lower head, H³, forming the outer or convex surface of the stave, the knives having hollow or concave cutting-edges. The blanks are fed to the cutters through feed-rollers N N³ on shafts N', the shaft of the upper roller being 45 journaled in boxes N², fitting in slots A' of the frame A and held down by springs N³, so that this upper roller will be allowed to rise slightly 50

to admit staves of different thicknesses, and yet be held down tight upon staves of all thicknesses. This upper roller is fluted or 55 serrated longitudinally, so as to take hold of and feed the blank through, and it is keyed to its shaft, as shown in Fig. 8. Its shaft is driven to feed the blank by a cog-wheel, O, thereon, meshing into a similar wheel, O', on a 60 shaft, O², provided with a pulley, O³, connected by means of a belt with a pulley, O', on the main driving-shaft B.

P P^x represent delivery-rollers on shafts P', the shaft of the upper roller being journaled 65 in movable boxes P², held down by springs P³, as and for the same purpose as in the case of the upper feed-roller. The tension of these springs N³ and P³ may be regulated by set-screws N⁴ P⁴, passing through the top plate of 70 the frame, as shown in Fig. 8. The upper delivery-roller is serrated and is keyed to its shaft, being turned by a cog-wheel, P⁵, meshing into the wheel O'. (See Figs. 2 and 3.) The upper delivery-roller has a convex and 75 the lower one a concave surface, as shown in Fig. 5, and the feed-rollers are similarly shaped.

In line with the upper part of the lower cutter and the lower feed and delivery rollers is a narrow table or strip, T, secured to the 80 frame of the machine, and upon which the blank is held as it passes through by a roller, U, on a shaft, U', journaled in a box, U², fitting in an opening, A², of one side of the frame A, as shown in Figs. 6 and 8, and held down 85 by an elastic cushion, U³, and set-screw U⁴. Just over the lower cutter is another roller, V, similar to that, U, having shaft V', box V², cushion V³, and set-screw V⁴, the box fitting in an opening, A³, of the frame A. These 90 rollers act to hold the stave in position, and they preferably have convex surfaces, as shown in Figs. 6 and 7. The stave is delivered beneath a roller, W, on a shaft, W', secured by a bracket, W², and bolts W³ to the frame of the 95 machine, (see Fig. 8,) the bolts passing through a slot in the bracket, so that the roller can be adjusted to suit staves of different thicknesses. This roller tends to hold the stave down to a 100 position in line with the feed and delivery rollers and cutters.

The two parts of the frame A are secured together by the rods A⁴. (See Fig. 2.)

I claim as my invention—

A machine for dressing staves which consists of a frame, A, in two parts secured together by tie-rods A⁴, main shaft journaled on one end of the frame, large pulley C and small 5 pulley O⁴, mounted on the main shaft, upper cutter-shaft, H', carrying cutter-head D³, pulley D, pinion O', and large pulley O³, feed-roller shaft N', carrying fluted roller N, and cog-wheel O, delivery-roller shaft P', carrying 20 fluted roller P, and cog-wheel P³, the cog-wheels meshing with the pinion, lower cutter-shaft, D', carrying cutter-head H³ and pulley

H, lower feed-roller, N³, lower delivery-roller, P³, narrow table T, between the lower feed-roller and the lower cutter-head, spring-rollers 25 U and V, to hold down the staves on each side of the upper cutter-head, and depressing-roller W, to prevent the upward movement of the staves, as set forth.

GEORGE J. FRITZ.

In presence of—
GEO. H. KNIGHT,
SAML. KNIGHT.
